UNITED STATES PATENT OFFICE.

EDWARD M. BENTLEY, OF LAWRENCE, NEW YORK.

ADVERTISING DEVICE.

SPECIFICATION forming part of Letters Patent No. 689,947, dated December 31, 1901.

Application filed January 19, 1897. Serial No. 619,807. (No model.)

To all whom it may concern:

Be it known that I, EDWARD M. BENTLEY, a citizen of the United States, residing at Lawrence, Queens county, State of New York, have 5 invented certain new and useful Improvements in Advertising Devices, of which the following is a specification, reference being made to the accompanying drawings, where-in—

10 Figure 1 is a side elevation, partly in section, of my apparatus; and Fig. 2 is a cross-section thereof on the line X X of Fig. 1.

My invention consists in an advertising device adapted to be placed along the line of an 15 electric railway and to be operated by the trolley or contact of the electric-railway cars as it passes along the line conductor of the railway. More particularly, it consists of an advertising-sign which is brought into operation 20 by means of a controlling circuit-closer located on or near the trolley-wire or conductor, which circuit-closer is adapted to be actuated by the trolley or contact each time 25 that it passes. The advertising device is preferably located at the side of the street along which the railway passes, either on a pole or on the side or even on the interior of a building, and the arrangement is such that it will continue in operation for a definite 30 length of time after the trolley has passed and will then be automatically thrown out of action and so remain until another trolley passes along, when the previous operation will be repeated.

35 The invention also resides in certain details of construction, which will be hereinafter described and claimed.

Referring to the accompanying drawings, A represents an ordinary trolley-wire of an 40 electric railway, which is suspended above the roadway in the usual manner.

B is an ordinary hanger or a plate of any suitable kind attached to the upper surface of the wire and supported from an insulating-block C. It serves as the base or framing for 45 maintaining the circuit-closer in its required fixed relation to the conductor. The insulating-block is contained in a metallic casing D, being held therein by a retaining-ring E, which engages the under side of a shoulder 50 on the block C and is bolted to the casing D. Within the casing and above the insulating-

block is a space within which is located the circuit-closer, designed to be operated by a trolley passing along the conductor A. The 55 hanger B is cut away at its center for a short distance, and in the center of the space thus formed is placed over the conductor a rod F, which extends upward through the insulating-block C into the aforesaid space above, 60 where it is provided with means for operating the circuit-closer. To the lower end of the rod F are jointed two plates G, split or slotted to embrace the plate or hanger B and having depending flanges on their lateral 65 edges. These two plates extend in opposite directions from the rod F, on which they are hinged or have a bearing at their inner extremities. The outer extremities of these plates rest loosely or have a suitable bearing 70 or hinge on projections H, placed one at each end of the hanger B. These projections H maintain the outer ends of plates G at a higher level than their inner ends, and pins extending through the said projections above the 75 plates hold the said outer ends down. These plates G are of such width that a trolley-wheel may pass freely between their depending side flanges, and being inclined the flanges of the trolley-wheel will strike the under side 80 of the plates G and gradually lift their inner ends as it proceeds, and thereby force the rod F upward, so as to operate the circuit-closer. There being two of these plates G, the direction of movement of the trolley-wheel is im- 85 material, as it will obviously operate the rod F in whichever direction it may be passing.

The hanger B is attached to the under side of block C by means of a central bolt K, which is itself centrally perforated, so as to receive 90 the rod F. The upper end of bolt K is screwed into a plate L, from the edges of which rise three standards M, which meet at a central point directly over the end of bolt K and sustain from such meeting-point the 95 cylinder N of a small dash-pot, of which the rod F forms the piston. The upper end of cylinder N is covered by a spring-plate O, which acts as a valve, permitting the rod F to be lifted freely, but retarding its movement 100 downward. By this arrangement the main moving or operating portions of the device are mechanically connected by strong and unvarying metallic parts independently of

the insulation, so that there can be no binding or sticking of the parts in operation. There is also no insulation introduced into the parts operated by the trolley.

- 5 A block P of insulating material is fastened between two of the standards M, and a curved spring R is fastened on the upper side of block P and thence passes around the block back of it and below it and terminates in front of it at a point lying in the path of a lug S, projecting from the rod F. This lug S is beveled, so that as it moves upward it will slide past the tip of spring R, which will then spring out, so as to engage the under side of the lug. 15 The rod F will then drop down gradually by reason of the weight of the plates G, attached to its lower end, and will draw down with it the end of spring R until the spring assumes the position shown in dotted lines, when its 20 tip will be drawn out from under lug S, letting the spring fly back into its original position. The rod F will be in electrical connection with the conductor A, while the spring R will form the terminal of a branch circuit. 25 Therefore this branch circuit will become energized each time that the lug S comes in contact with the tip R and will remain energized until the rod F drops and the spring R is released from the lug, when it will fly back and 30 open the circuit quickly and widely. The branch circuit which is thus controlled by the described circuit-closer may be employed to operate an electrical advertising device of any description, a very simple one being 35 shown in Fig. 1 as a transparent casing located on a post at the side of the street and containing five or six incandescent lamps in series. On the transparent surface of the casing any advertising lettering or device may 40 be inscribed.

It is obvious that any other electrically-operated sign or advertisement may be substituted for that described, and it is also to be understood that the retarding or timing apparatus of the advertiser may be of any other description than that herein illustrated and also that other means may be provided for causing the trolley to control the said advertiser, as I do not intend to limit myself to 45 the specific devices herein set forth, there being various substitutes therefor which may be employed without departing from the spirit of my invention.

What I claim as new, and desire to secure 50 by Letters Patent, is—

1. The combination with an electric-railway conductor of a traveling contact, an electrically-operated advertiser at a fixed point along the line, a circuit for said advertiser 55 and a timed circuit-controller therefor placed in the path of the said contact, so as to be operated thereby.

2. The combination with an electrically-operated advertiser at a stationary point along 60 an electric railway, of a branch circuit from the conductor of said railway extending to

said advertiser for operating the same, and a controller for said circuit placed adjacent to the line conductor of the railway, so as to be operated by a traveling contact thereon. 70

3. The combination with a plate or hanger B adapted to be attached to an electric-railway conductor, of an insulating-block C, a bolt or connection K, a plate L attached to said bolt on the opposite side of said insulating-block, and a circuit-controller mechanically connected to said plate and provided with an operating device mechanically connected to said plate B, whereby all of the operating parts are mechanically independent 80 of the said insulating-block.

4. The combination with a plate or hanger B adapted to be attached to an electric-railway conductor, of vertically-moving rod F, and horizontal plates G extending laterally 85 in opposite directions from the said rod and bearing thereon at one end and at the other end bearing on the said plate or hanger so as to engage the trolley-wheel flanges and actuate the said rod F. 90

5. The combination with a plate or hanger B adapted to be attached to an electric-railway conductor, of a rod F placed centrally above the conductor and an operating-plate extending laterally therefrom so as to engage 95 the trolley-wheel flanges.

6. The combination with inclined plate G placed above electric-railway conductor A and extending laterally on opposite sides of the conductor, so as to engage the flanges of 100 a trolley-wheel on the said conductor, and a circuit-controller operated by the said plate.

7. The combination with an electric-railway conductor of a circuit-closer adapted to be operated by a traveling contact on the 105 said conductor, and an intermediate operating device placed in the path of said trolley-wheel, so as to be actuated thereby and provided with depending side flanges for preventing derailment of the trolley during the 110 time that it is operating the said circuit-controller.

8. The combination with an electrically-illuminated advertising device, of a circuit containing the electric lamps of said device, 115 and a controller for said circuit placed at a point adjacent to the conductor of an electric railway and provided with operating devices placed in the path of a traveling contact on said conductor, so as to be actuated thereby. 120

9. The combination with the rod F and line conductor A, of the plate G having depending side flanges and a connecting device at one end for engaging the rod F and at the other end a device for engaging a projection 125 on the upper side of conductor A.

In witness whereof I have hereunto set my hand this 4th day of January, 1897.

EDWARD M. BENTLEY.
